Patented June 22, 1965

201,438

CABINET FOR ELECTRONIC INSTRUMENTS

Monte L. Levin, Roslyn Heights, N.Y., assignor to
Vacuum-Electronics Corp., Plainview, N.Y.

Filed Apr. 16, 1964, Ser. No. 79,525

Term of patent 14 years

(Cl. D26—5)

FIG. 1

FIG. 2

1-4

Des. 201,438

PAGE 2

FIG. 3

FIG. 4

FIG. 5

FIG. 1 is a top plan view of a cabinet for electronic instruments showing my new design;

FIG. 2 is a front elevational view thereof;

FIG. 3 is an end elevational view thereof;

FIG. 4 is a sectional view taken on the line 4—4 of FIG. 2; and

FIG. 5 is a perspective view thereof.

The end not shown is the same in appearance as the end shown, and the back is conventional.

I claim:

The ornamental design for a cabinet for electronic instruments, substantially as shown and described.
